AUTOMATIC DAMPER CONTROL

George E. Stringer, Chicago, Ill.

Application October 29, 1938, Serial No. 237,753

8 Claims. (Cl. 126—285)

This invention pertains to control mechanism for use with heating and combustion systems employing a damper or analogous device, a principal object being the provision of mechanism coacting with a damper and an electrically operated or controlled fuel supplying means for opening the damper more or less completely at the instant the heating or combustion device is set into operation and thereafter closing the damper more or less completely when combustion has been in progress a predetermined length of time.

Viewed from another aspect, it is an important object of the invention to provide control mechanism for use with oil burners, stokers, and analogous combustion devices in which the fuel supplying means is electrically operated or controlled and in which there is an ignition device for igniting the fuel when the fuel supply means is energized, the control mechanism including electrical means arranged in circuit with the fuel supplying and ignition means so that when the fuel supplying and ignition means are energized the damper will be opened more or less completely, there being mechanism arranged to cut out the ignition means as soon as combustion is in progress, and the control mechanism coacting with the ignition cut-out means to permit and effect closing of the damper to greater or less degree, the control mechanism further coacting with the fuel supply means so that the damper will be entirely closed when the fuel supply means is cut off or deenergized.

In still another of its aspects, the invention provides automatic control means for use with oil burners, stokers, and analogous combustion devices for increasing the efficiency of such devices, for obviating dangers due to initial combustion flashes, and for preventing the formation of obnoxious gases, fumes, and the like, due to initial combustion reaction in those arrangements where the damper is normally closed to greater or less degree, the control mechanism being arranged to effect opening of the damper to permit easy egress of the combustion gases when the combustion device is set into operation, as by pumping and igniting an oil spray, or when fuel is additionally fed into the fire, as in the case of an automatic stoking device.

A specific object of the invention is the provision of control means including a plurality of electromagnets arranged for joint and several operation to open and close a damper various amounts, the electromagnets being arranged in circuit with fuel supply and igniting means so

that the damper will be entirely opened at the time of ignition and subsequently closed a certain amount either due to a lapse of time or due to the establishment of a predetermined temperature in the flues or other part of the system.

Other objects, advantages, and economies residing in the invention pertain to certain details of construction and operation of the parts of the illustrative embodiment described hereinafter in conjunction with the annexed drawing, in which:

Fig. 1 is a front elevation of the control operating mechanism;

Fig. 2 is a vertical side section along line 2—2 of Fig. 1, including the damper;

Fig. 3 is a circuit diagram; and

Fig. 4 is a modified circuit diagram.

The control mechanism of my invention is intended for use with combustion devices, such as oil burners and stokers, which employ a breeching or flue 10 (Figs. 1 and 2) communicating with the combustion chamber from a stack, and which are provided with a damper 11 pivotally mounted as at 12 to swing into opening and closing position across the flue 10, the damper being shown in closed position in Fig. 2.

The damper 11 swings about a horizontal axis on a spindle 13 secured thereto by the screw means 14 in a struck-up sleeve portion 15 according to the usual damper construction, the spindle extending through a sleeve 16 which terminates in a bushing 17 on the back wall 18 of a housing 20, an end of the spindle being secured in the hub 21 of a lever arm 22. Rocking of the arm 22 effects movement of the damper into various open and closed positions, and this arm is provided with an extension 23 on which is a counterweight 24 normally lowered against a stop 25 to turn the damper into completely closed position.

Means for moving and maintaining the damper 11 in various open positions, includes the provision of lever mechanism including members which are jointly or severally operable to effect movement of the damper different amounts toward open position. In one of its forms, this mechanism includes a link 30 pivoted as at 31 to the arm 22 and pivotally connected as at 32 between the ends of a differential lever arm 33. Pivotally connected as at 34 and 35 to the opposite end portions of the arm 33, are links 36 and 37, the latter in turn being pivotally connected as at 38 and 39 to reciprocable driving members or plungers 40 and 41 arranged for back and forth movement in parallel lines transverse to the pivotal axis of the damper spindle 13.

It will be observed that the driving members

40 and 41 may be moved downwardly together with a resultant downward pull on the damper operating arm 22, due to the connection of the driving members through the differential arm 33 5 and the link 30 with the damper arm 22.

It will also be observed that either of the driving members 40 or 41 may be pulled down alone with a resultant downward pull on the link 30 and hence on the damper operating arm 22; however, in the latter case, due to the differential connection 33 with the link 30, the damper arm 22 will be moved a lesser distance when only one of the actuating or driving members 40 or 41 is pulled down than would be the case if both of 15 the latter members operated together. Thus, the several movements of the differentially connected driving or actuating components of the lever mechanism will open the damper a predetermined amount, whereas the joint operation 20 of the components of the differential means will move the damper a greater amount.

The means for actuating the differential mechanism is preferably electrically energized and includes a pair of solenoids 42 and 43 each 25 mounted on the wall panel 18 beneath one of the members 40 or 41, the latter being magnetically attractive and constituting cores or armatures for the solenoids, and being drawn downwardly when either of the solenoids is energized.

30 In one circuit arrangement, illustrated in Fig. 3, suitable for use with stokers or certain types of burners omitting ignition means, one terminal of the solenoid winding 43 is connected by a conductor 45 to one terminal of a heating element 46, the remaining terminal of the latter being connected by conductor 47 to one contact 53 of a thermostatic master control switch, the remaining contact 54 of which switch is connected to one terminal 48 of the power line, while the 35 remaining terminal of the solenoid winding 43 is connected by conductor 50 to one terminal of the electrically energized fuel supply means 51, in this case a motor, the remaining terminal of the latter being connected by conductor 52 to the return side or terminal 49 of the power line. Thus, the damper actuating solenoid 43 is connected in series with the heating element 46 and the fuel supplying means or motor 51 so that 40 when the thermostatic switch 53 is closed, the fuel supply means or motor is automatically 45 started.

In the arrangement of Fig. 3, the ignition means may or may not be employed, depending upon the nature of the combustion system, whether it is of the intermittently operable or 50 continuously operable type.

In the case, for example, of an oil burner, one terminal of an ignition coil 55 is connected by a conductor 56 to one contact 57 of a shunting switch and also to the terminal 49 of the power line (in common with the conductor 52 on the motor), the opposite terminal of the ignition coil being connected to the remaining terminal 58 of the shunting switch and also via conductor 59 to one of the terminals 60 of a thermostatic 55 time-delay switch actuated by the heating element 46, the remaining terminal 61 of the time-delay switch being connected by conductor 62 to one terminal of the solenoid winding 42, and the remaining terminal of the latter being connected 60 by conductor 63 to the contact 53 of the master 75

thermostatic switch and through the latter to the remaining terminal 48 of the powerline. Thus, the solenoid 42 is connected in series with the switch means 46-60-61, and also with the ignition coil 55, depending upon whether the 5 shunt switch 57 is open or closed.

Assuming the arrangement of Fig. 3 to be used in conjunction with an oil burner employing an ignition coil 55, the shunt switch 57 may be opened, and as soon as the master thermostatic 10 switch closes, current will flow in one side circuit through the solenoid winding 43, the time-delay heater element 46, and the motor 51, and at the same time through another side or branch circuit including the ignition coil 55, the contacts 15 of the time-delay switch 60-61 and the winding of the solenoid 42. Operation of the master thermostatic switch 53 will therefore effect simultaneous energization of both of the solenoids 42 and 43 and also of the ignition coil and 20 the motor, and as a result of the energization of the solenoids both of the members 40 and 41 (Fig. 1) will be pulled down to the limit of their movement, with a consequent pivoting of the 25 damper operating members 22-23-24 into the uppermost dotted line position corresponding to 25 fully open position of the damper.

Upon closing of the master thermostatic switch 53, the electrically energized operating or control means, that is, the motor 51, for the fuel supplying mechanism (i. e. a pump, blower, injection means, stoker or the like), will feed fuel into the combustion chamber for ignition by the operation of the coil 55, and the gases and pressure in the combustion chamber, resulting from the initial reaction of ignition, will be provided with a means of egress through the flues in the usual manner due to the fact that the damper 11 has been opened by joint operation of the solenoids 42 and 43. After combustion has been in progress for a relatively short interval, the time-delay or thermostatic switch means 46-60-61 will open and deenergize the solenoid 42, with the result that the plunger 40 and the corresponding side of the differential lever 33 will move upwardly, this movement being limited by a stop 44 (Fig. 1) so that the damper lever means 22-23-24 will be permitted to drop back to the intermediate dotted line position shown in Fig. 1, with a resultant partial closing of the damper so that less of the heat will be permitted to pass up the flues. When the normal predetermined temperature has been restored in the heated compartment, the thermostatic switch 53 will open, stopping the fuel supplying means and de-energizing the solenoid 43 with a consequent upward movement of the plunger 41 of the latter and a consequent restoration of the damper lever means 22-23-24 to its initial (full line) 55 position.

In the event that the combustion system is of the continuous operation type, for example, a stoker-fired furnace, the ignition means 55 will not be needed and is shunted out of the circuit 65 by closing the switch 57. In other respects, the circuit arrangement of Fig. 3 will then operate in the same manner as when used with an oil burner. The time-delay switch means 46-60-61 is preferably mounted on the panel 70 18 along with the solenoids, and may be of the adjustable type, if desired.

Another circuit arrangement which is particularly suited for use with oil burners is shown in Fig. 4, wherein one terminal of the solenoid 75

winding 42 is connected by a conductor 70 to one terminal 71 of a thermostatic switch whose remaining terminal 72 is connected by conductor 13 to a terminal of an ignition coil 74, and the 5 remaining ignition coil terminal is connected to a contact 75 of a master thermostatic switch having a contact 76 connected to one terminal 77 of the power line, the opposite terminal 78 of which is connected by a conductor 79 to the 10 remaining terminal of the solenoid winding 42. Thus, one of the damper operating solenoids is connected in series with a thermostatic stack switch, the ignition coil, and the master thermostatic switch. 15

One terminal of the other solenoid winding 43 is connected by a conductor 80 to the master thermostatic switch contact 75 and through the latter to one side of the line, the remaining terminal of the winding 43 being connected by a 20 conductor 81 through the fuel supply means or motor 82 and a conductor 83 to the return side 78 of the power line. When the master switch 75—76 is closed, both the ignition coil and the fuel supply means or motor are energized simultaneously with the two solenoids 42 and 43. The thermostatic stack switch 71—72 is normally 25 closed and is preferably situated in the flue or stack in a position to be heated by the hot gases issuing from the combustion chamber. 30 When the two solenoids pull up, the damper is opened and an exhaust opening through the flues provided for the increase in pressure and the gaseous products of combustion resulting from the initial combustion reaction. The stack switch 71—72 is preferably arranged to open as a result of heating by the exhaust gases a short 35 time after combustion is started, the period of time being in all cases adequate to permit the proper conditions of pressure to be established 40 in the combustion line and to assure that all obnoxious gases, smoke, and the like, will have been carried up the flue.

When the switch 71—72 opens, the solenoid 42 will be deenergized and the damper operating 45 lever 22 will be permitted to assume the intermediate position heretofore described and corresponding to partly open position of the damper. At the same time the ignition coil 74 will be cut out of the circuit. Opening of the master switch 50 75—76 will deenergize the motor and the remaining solenoid, and the damper will be restored to fully closed position.

Other forms of time-delay or supervisory switching means may be used in place of the 55 heater-operated switch means 46—60—61 of Fig. 3 or the ordinary thermostatic switch 71—72 of Fig. 4, and, if desired, the circuits respectively controlled by the aforesaid switching means may be placed directly under manual control in installations where such an arrangement is desirable. Moreover, the circuit of Fig. 4 may be used in conjunction with heating plants which 60 do not employ an ignition means but are in constant operation, the stack control switch or equivalent means being arranged for operation by a rise in temperature in any convenient part of the combustion line.

The objects and advantages of the invention 70 may be realized by other forms of construction and modes of operation of the arrangements described in detail for purposes of illustration, and it is a condition of this disclosure that the appended claims are to include all equivalent means and arrangements.

Having thus described my invention, what I

claim as new and desire to protect by Letters Patent is:

1. Control mechanism for use with dampers and analogous devices, said mechanism including in combination, an operating member adapted 5 for operative connection with a damper or the like, a pair of solenoids each having a plunger movable substantially collaterally with respect to the plunger of the other, and linkage means operatively interconnecting said plungers and 10 said operating member for movement of the latter different amounts from a normal position when said plungers are attracted by their respective solenoids, the amount of movement of said operating member depending upon the 15 number of said solenoids operated at a given time, means yieldingly urging said operating member into said normal position, and means for selectively energizing said solenoids to actuate the same simultaneously or separately. 20

2. In combination, a damper arranged for pivotal movement from normally closed to open position, means for pivoting said damper, means operatively associated with said lever means for yieldingly urging said damper toward 25 closed position, a pair of magnetically attractable members arranged for back and forth movement side by side in the same direction, link means connected with each of said magnetically attractable members, a differential lever arm 30 pivotally interconnecting the aforesaid link means, means pivotally connected with said lever means and with said differential arm at a point on the latter between the pivotal connections thereof with said link means whereby said lever 35 means may be pivoted by joint or independent movement of said magnetically attractable members, the distance which said lever means is pivoted depending upon whether one or both of said magnetically attractable members is operated at a given time, and electrically energized means for attracting and moving said magnetically 40 attractable members in the same direction from a normal position corresponding to the normal position of said lever means, and means 45 for energizing said electrically energized means singly or together.

3. Damper control mechanism including a damper operating lever, a plurality of solenoids each having an armature movable back and 50 forth in the same direction, means operatively linking said lever with said armatures for movement of the lever by one or more of said armatures when the latter are attracted by their respective solenoids, said means comprising a differential lever arm pivotally connected between its ends to said damper operating lever, a plurality of link means having pivotal connection with said differential arm at points on opposite sides of the connection of said arm with said operating 55 lever, each of said link means in turn having pivotal connection with one of said armatures, means coacting with the damper and said operating lever for moving the latter and said armatures into a normal position, the degree of movement of said operating lever from normal position 60 depending upon the number of solenoids operated at a given time, and means for energizing said solenoids separately or together. 65

4. In a control mechanism for a damper, a pair 70 of collaterally reciprocable operating members, a differential lever pivotally linked with each of said members, a damper operating lever having pivotal connection with said differential lever at a point between the linkage of the latter with 75

- said operating members, and electrical means operable selectively for moving said operating members jointly or severally to displace said operating lever different amounts.
5. The combination, with a damper, of operating means for moving the same different amounts, said operating means comprising a pair of solenoids and means for energizing the same jointly or severally, each solenoid having a plunger attractable thereby, link members each pivotally attached to an end of one of said plungers, a differential lever arm having opposite end portions each of which is pivotally connected with one of said link members, and a damper operating lever having pivotal connection with said differential arm at a point between the ends of the latter and having pivotal connection with said damper.
6. A control device including a main operating lever and a differential lever pivotally attached between its ends to said main operating lever for pivotal movement in opposite directions, electrically actuated devices each having operative connection with one of said opposite ends of the differential lever for operation severally to pivot said lever in opposite directions and thereby move said main operating lever a certain distance, said electrically actuated devices being operable jointly to move said main operating lever a greater distance resulting from the bodily displacement of said differential lever by joint action of said electrically actuated devices.
7. In a damper control, a pivotable lever ar-

ranged to move a damper, and means yieldably urging said damper lever into a normal position, an operating lever having pivotal connection at one end with said damper lever, an opposite end portion of said operating lever being pivotally connected between the ends of a differential lever arm, a pair of solenoids each having a plunger arranged for collateral reciprocation in the general direction of movement of said operating lever into and out of normal position, and a link pivotally connecting the end of each plunger with an end of said differential arm, said solenoids being connected in a control circuit for energizing the same jointly or severally, said plungers being withdrawn from attracted position by action of said yieldable urging means.

8. In a damper control, a damper operating member and means for displacing said member different amounts from a normal position and comprising a plurality of electromagnets each having an armature member operatively associated with said operating member for joint or several coaction therewith and arranged and constructed to displace the same different amounts dependent upon the number of said electromagnets operated at a given time, minimum displacement being effected by the least number of electromagnets operated as aforesaid, and maximum displacement being effected by the greatest number of electromagnets operated at a given time as aforesaid, and means yieldingly urging said operating member into said normal position.

GEORGE E. STRINGER.
